UNITED STATES PATENT OFFICE

95,627

DESIGN FOR A RECIPE CABINET

Charles E. Bisbey, Metaline Falls, Wash.

Application February 4, 1935, Serial No. 55,242

Term of patent 7 years

To all whom it may concern:

Be it known that I, Charles E. Bisbey, a citizen of the United States, residing at Metaline Falls, in the county of Pend Oreille and State of Washington, have invented a new, original, and ornamental Design for a Recipe Cabinet, of which the following is a specification, reference being had to the accompanying drawing, forming part thereof.

The figure is a perspective view of the recipe cabinet, showing my new design.

I claim:

The ornamental design for a recipe cabinet substantially as shown.

CHARLES E. BISBEY.
